ADJUSTABLE SPRINKLER

Wallace S. Pangborn, Detroit, Mich., assignor to
Charles B. Kemp, Grosse Pointe, Mich.

Application August 21, 1946, Serial No. 692,030

4 Claims. (Cl. 299—69)

1

My invention relates to adjustable sprinklers and more particularly to a nozzle construction for such device.

The desirability of means for adjusting the spray of water sprinklers has long been recognized and is evidenced by the prior art in this field. Numerous sprinklers of this type have heretofore been manufactured which permit adjustment of the spray from a fine mist to large droplets of water. However, in addition to adjustability of the quality or type of spray, it is proposed to provide means for varying the direction of a spray from such devices. That is to say, in most instances a high spray which covers a large area of ground is desired, but under some conditions, such as water under small trees and bushes, a low directed spray is most suitable.

It is therefore an object of the present invention to provide a water sprinkler having means for adjusting the direction as well as the quality of the spray produced. Another object is the provision of a nozzle which accomplishes this result which is simple in both construction and operation.

In the drawings:

Figure 1 is a side elevation of a conventional rotor type sprinkler embodying my invention.

Figure 2 is an enlarged side view of a nozzle of my invention.

Figure 3 is an end view of the nozzle showing two alternate positions of the nozzle cap.

Figure 4 is a sectional view through 4—4.

Figure 5 is a side view of one of the component parts of my invention.

Figure 6 is an end view of the member shown in Figure 5.

Figures 7 and 8 show a modified form of my invention.

Figure 9 illustrates the operation of a water sprinkler of my invention.

Referring now to Figure 1 it will be seen that a rotor type sprinkler is shown having a base 11, a hose coupling 12, a body 13, a vertical member 14, and tubular arms 15 mounted to rotate freely above member 14. Water enters the body 13 at the hose coupling 12, passes through the vertical member 14 to the arms 15 from which it is angularly discharged to impart a rotating motion to said arms 15. Since the details of construction of this type of sprinkler are generally known further description is believed to be unnecessary.

The principal features of my invention reside in the nozzle construction provided at the ends of arms 15. Into the discharge end of arms 15 are press fitted inserts 16 shown in Figures 5 and 6

2

having an annular groove 17 and circular longitudinal passages 18 and 19. The centers of said passages are preferably located within one of the lower quadrants defined by a horizontal and vertical line through the center on the end face of said insert 16. The reason therefore will be presently explained. As best shown in Figures 2 and 4, caps 20, fitted over the end of arms 15, serve as nozzles for the spray. Said caps have a conical end portion 21, a knurled portion 22, and an annular flange 23. On the inside of said cap, the body 24 is adapted to seat against the outer face of insert 16 and is provided with an angularly disposed orifice 25 which is adapted to cooperate with either of said passages 18 and 19 when said cap is rotated. The cap may also be rotated to a position where orifice 25 is aligned with neither of said passages to shut off the discharge from the nozzle.

20 In order to permit rotation of said cap 20 and yet firmly retain it against the face of insert 16, the flange 23 is indented at 27 after assembly to cooperate with the annular groove 17 on the insert 16. The indenting pressure is controlled so that the cap may be rotated by grasping it at the knurled section 22 and yet is sufficient to provide a relatively leak-proof connection between said cap and arm 15. To facilitate adjustment of cap 20 suitable markings are impressed 30 on arm 15 and flange 23 as at 28 and 29 respectively to indicate the relative position of said cap on arm 15 when orifice 25 is aligned with passages 18 and 19.

It will thus be seen that when cap 20 is rotated 35 to a position where orifice 25 is aligned with passage 18 a low spray will be directed from the nozzle and when orifice 25 cooperates with passage 19 a high spray will be produced. Likewise, when orifice 25 is in complete alignment with either passage 18 or 19 a heavy spray is obtained 40 which can be reduced to a fine or highly dispersed spray by rotation of cap 20 so that the orifice 25 is slightly out of alignment with either one of said passages 18 or 19.

45 By locating passages 18 and 19 in the same lower quadrant, as described above, caps 20 may be adjusted so that a high spray will be produced by one nozzle and a low spray by the other, as shown in Figure 9, and, at the same time, the 50 impulse pressure on each nozzle will produce the same direction of rotation of all arms 15. In the modified form of construction shown in Figures 7 and 8 larger passages 18' and 19' and a larger orifice 25' are provided. In this instance the size of passages 18' and 19' prevent their loca-

tion in the same quadrant and therefore best results are obtained when both nozzles are adjusted to the same elevation.

To obtain a spray of greater intensity either nozzle may be rotated to shut off completely the spray therefrom. With this type of adjustment discharge of a high or low spray will continue at the other nozzle but with greater force and volume. This permits sprinkling at greater distances without movement of the sprinkler.

Thus it will be seen that the nozzle construction herein described is simple in both construction and operation and the provision of selective water passages permits adjustment of the water spray in both quality and direction.

What is claimed is as follows:

1. A nozzle construction for a water sprinkler of the type having tubular arm members mounted to rotate freely on a water receiving body comprising plugs press fitted into the discharge ends of said tubular members, said plugs having a plurality of outlet openings in the outer end face thereof for the discharge of water therethrough, said openings being spaced eccentrically of the axis of said tubular members, and a head member for controlling the discharge of water from said outlet openings, said head having a sleeve portion telescoped over the outer surface of said tubular member at the discharge end thereof and a body portion extending axially outwardly from said sleeve portion, said body portion having an inner face in coplanar engagement with the outer end face of said plug and having a discharge passage therein extending obliquely to the axis of the tubular member on which it is supported, said discharge passage terminating at the inner face of said body portion in an off-center orifice adapted to register selectively with the discharge openings in said plug member to discharge water from said head at variable angles of elevation relative to the plane of rotation of said tubular members, and means for retaining said head member at the discharge end of said tubular member with said inner face of said body member in coplanar engagement with the outer end face of said plug.

2. A nozzle construction for a sprinkler of the type having tubular arm members mounted to rotate freely on a water receiving body comprising plugs press fitted into the discharge ends of said tubular members, each of said plugs having an outer end face and a plurality of passages therethrough terminating in a plurality of off-center, vertically spaced outlet openings in said end face, and head members for controlling the discharge from said outlet openings, each of said head members having a sleeve portion telescoped over the discharge end of one of said tubular members and a cap portion having an inner face in coplanar engagement with said end face of one of said plugs, said sleeve being annularly indented to cooperate with an annular groove adjacent the end of said tubular member for rotatably retaining said head on the end of said tubular member, said cap portion having a passage extending therethrough obliquely to the

axis of the tubular member on which it is supported and terminating in an orifice at said inner face which, when said head is rotated, is adapted to be brought into registry with any of said outlet openings whereby the water in said tubular members may be discharged at variable angles of elevation relative to the plane of rotation of said tubular members.

3. A nozzle construction for a water sprinkler device of the type having tubular arm members mounted to rotate freely on a water receiving body comprising plugs press fitted into the discharge ends of said tubular members, each of said plugs having an outer end face and a plurality of discharge passages therethrough terminating in a plurality of eccentrically disposed and vertically spaced outlet openings in said face, and head members rotatably secured at the discharge ends of each of said tubular members for controlling the discharge of water from said outlet openings, each of said head members having an inner face in coplanar engagement with said end face of one of said plugs and having a discharge passage therethrough, said discharge passage extending obliquely to the axis of the tubular member on which the head is supported and terminating at the inner face of said head in an off-center orifice which is adapted to be brought into and out of registry with any of said outlet openings in said plug and into partial registry with any of said openings and out of registry with all of said outlet openings whereby the water in said tubular members may be discharged from the ends thereof as a low spray when said orifice is brought into registry with one of said outlet openings, as a high spray when brought into registry with another of said outlet openings or as a highly dispersed spray when in partial registry with one of said openings and whereby the discharge may be prevented altogether by rotating said head so that said orifice is out of registry with all of said outlet openings.

4. The combination set forth in claim 3 wherein the outlet openings on each of said plugs are positioned relative to the axes of said tubular members such that, when said orifices on each of said heads are aligned with any of the outlet openings on said plugs, the water issuing from each of said oblique passages tends to rotate each of said tubular members in the same direction on said water receiving body.
